WILLIAM J. TURNER, OF PROVIDENCE, RHODE ISLAND.

VENT AND CLOSURE FOR REGULATING TANKS AND THE LIKE.

1,289,317.

Specification of Letters Patent. Patented Dec. 31, 1918.

Application filed April 6, 1916. Serial No. 89,360.

To all whom it may concern:

Be it known that I, WILLIAM J. TURNER, a citizen of the United States, residing at Providence, in the county of Providence and State of Rhode Island, have invented new and useful Improvements in Vents and Closures for Regulating Tanks and the like, of which the following is a specification.

This invention relates to improvements in vents and closures for regulating tanks. More particularly it relates to tanks in which the level of water or other liquid varies, and in which there is a vent above the water level which must be closed when the water rises enough to be in danger of escaping through the vent. It is here shown as it may be applied to a tank which is normally open to atmospheric pressure through a vent in the top; but which is liable to become filled with liquid under pressure and under circumstances in which it is important that the vent should be closed with certainty at a predetermined level. Hitherto it has been proposed to use floats for closing such a vent, but the present invention is intended to provide a more powerful and positive closure, one which is particularly adaptable for use in closing the escape from a regulating tank such, for example, as may be used for controlling the fire under the boiler in a steam heating system operating ordinarily under so called "vapor" or low pressure but susceptible of operation under higher pressure. Such a system is shown in my copending application for patent, Serial No. 89,358, in which case is also illustrated the use of a tank with vent closure like that herein set forth. The objects of the invention are accomplished by providing at the top of the tank a flexible diaphragm which may be set horizontally and arranged with a tube passing centrally through it with an air tight joint projecting a suitable distance below it and above it, and associated with a stationary conical plug the precise position of which may be adjustable but which the upper end of the tube engages whenever the tube is lifted sufficiently, and to which it may be lifted by upward flexure of the diaphragm. Rising water in the tank, reaching the bottom of the tube, seals the air contained in the tank below the diaphragm and above the level of the bottom of the tube. Water may continue to rise freely through the tube, but in the tank outside of the tube it can rise only by compressing the

air sealed therein. This pressure is transmitted to the diaphragm, pressing it upward with a force which is proportionate to the area of the diaphragm. The diaphragm may yield until the upper end of the tube which it carries encounters the plug. The parts are designed and set so that this happens before the water that is simultaneously rising in the tube, has reached the top. Thereafter the top of the tube is closed; and no matter how high the pressure may rise within the tank the closure is maintained by a force many times greater than the force which the water in the tube, or the air confined above it, can exercise upon the plug, because of the many times by which the area of the diaphragm exceeds the area of the tube, as well as because of the higher degree of pressure of the air sealed in the tank when the level of the bottom of the tank was reached as compared with that which was subsequently sealed within the tube when the plug was seated against its upper end. Upon the relief of pressure forcing water upward within the tank, the diaphragm returns, both by gravity and by its own elasticity, to its normal position, thus lowering the tube and restoring atmospheric communication with the interior of the tank. As compared with float-operated closures, it will be seen that this action is positive and of unlimited power, whereas the power of a float is limited by the buoyancy of the float. The invention may be embodied in various forms and is not limited to the specific arrangement chosen for illustration. It is intended that the patent shall cover by suitable expression in the appended claims whatever features of patentable novelty exist in the invention disclosed.

In the accompanying drawings:

Figure 1, is a side elevation of apparatus embodying invention, in medial section;

Fig. 2 is a plan of the same in section on the line 2-2 of Fig. 1; and

Fig. 3 is a plan of the device of Fig. 1.

Referring to the drawings 10 indicates the shell of a tank which is elongated vertically and which as here represented is supported at one end of a lever 11 capable of swinging up and down through a limited arc in order to control the position of the dampers and drafts which in turn control the fire under a boiler. These various parts are not shown as they are not part of the invention here claimed, but are mentioned merely to ex-

plain the connection in which the invention may be utilized in one of its forms of application. In the upper part of the tank is a horizontal diaphragm 12 which closes the tank air tight except for a passage which extends vertically through it and except for the supply pipe 14 for water which is connected to the lower part of the tank. In the middle of the diaphragm 12 is a sleeve 15 5 penetrating the diaphragm and having a head 16 on one side of the diaphragm and a screw thread 17 on the other side of the diaphragm; a washer and nut 18 screwed upon it being adapted to clamp the diaphragm so firmly that nothing can escape around the sleeve. The sleeve 15 has a tubular extension downward, 19, and one upward, 20, constituting a vent. The top end of the tube is countersunk conically as at 21 10 in order to make it fit a conical plug 22 which is supported rigidly above it, with its axis substantially coinciding with the axis of the tube on a bridge 23 in which it is adjustable by a screw thread and head 24 15 toward and from the end of the tube. In the operation of such a device, liquid flows into or out of the tank, owing to any cause, depending upon the nature of the apparatus in which the tank is used. In the particu- 20 lar case referred to liquid flows in when increase of pressure in the "vapor" in the boiler causes a rise of water in this outside connected leg which is open to the atmosphere. When the water has risen as far as 25 the bottom of the tubular section 19, the air remaining between that level and the diaphragm 12 is separated from connection with the atmosphere. A further influx of water causes a compression of this separated 30 air and also drives some of the water up through the tubular parts 20 and 19 which remain open to the atmosphere. However, the compression of air under the diaphragm presses the diaphragm upward, and as the 35 diaphragm yields the tube moves upward until its upper end encounters and is closed by the plug 22. The distance of its movement before this happens may be controlled by varying the setting of the plug in its bridge 23. When the end of the tube is 40 seated against the plug it is pressed thereagainst by substantially the entire pressure that is acting on the diaphragm which is of relatively large area as compared with the 45 area of the tube. This differential maintains a firm closure at the point, either as against the escape of air contained in the tube or the escape of water. The valve is at any time easily accessible for examination 50 or for repair. While a conical plug is illus- 55 trated it is obvious that another type of valve or seat might be substituted at pleasure. Furthermore the rise of the tube, which is executed with force corresponding to the 60 65 intensity of pressure on the water and the

area of diaphragm, can be utilized to operate any simple mechanism, such as a valve of different type, or an alarm, or extra damper, after the tube has begun to rise and before it has been positively stopped. 70

I claim as my invention:

1. In combination, a tank wherein the level of liquid may vary, said tank being closed to atmosphere except at a vent that is normally open, and having a flexible diaphragm forming part of the tank wall; a passage extending to said vent from a lower part of the tank where said variation of level may occur; and closing means for the vent, adapted to be made effective by outward flexure of 80 the diaphragm. 75

2. In combination, a tank wherein the level of liquid may vary, said tank being closed to atmosphere except at a vent that is normally open, and having a flexible diaphragm 85 against which contents may press; a tube mounted on the diaphragm, hermetically joined thereto exteriorly, internally providing said vent, and extending thereto from a lower part of the tank where said variation 90 of level may occur; and closing means for the vent adapted to be made effective by flexure of the diaphragm. 95

3. In combination, a tank wherein the level of liquid may vary, said tank being closed 95 to atmosphere except at a vent that is normally open, and having a flexible diaphragm against which contents may press; a tube extending to said vent from a lower part of the tank where said variation of level may 100 occur; and closing means for the vent, adapted to be made effective by outward flexure of the diaphragm, comprising a plug valve adjacent to the outer end of the tube and adapted close it. 105

4. In combination, a tank wherein the level of liquid may vary, said tank being closed to atmosphere except at a vent that is normally open, and having a flexible diaphragm against which contents may press; a tube extending to said vent from a lower part of the tank where said variation of level may occur; and closing means for the vent, adapted to be made effective by outward flexure of the diaphragm, comprising 110 a plug stationarily mounted at the end of the tube, against which the tube abuts when moved outward. 115

5. In combination, a tank wherein the level of liquid may vary, said tank being closed to 120 atmosphere except for a vent that is normally open, and having a flexible diaphragm against which contents may press; a tubular core penetrating the diaphragm and having flanges adapted to be clamped together upon 125 the diaphragm, whereby said vent is made; a tubular extension of said core downward to a part of the tank where the said variation of level may occur, and means outside of the tank for closing the said vent, adapted 130

to be made effective by outward flexure of the diaphragm.

6. In combination, a tank adapted in its lower part for connection to a source of liquid supply, and at its top closed to atmosphere except at a vent provided therein; having a flexible diaphragm as a part of its said upper closure, and a tube from said vent to a level below the diaphragm, whereby air is sealed in the upper part when liquid rises above the bottom of the tube; and a conical plug closure for the vent, one for the two parts of the vent closure being connected with the diaphragm so that the two parts of the closure are brought together by flexure of the diaphragm resulting from pressure of said sealed air upon it occasioned by further rise of liquid.
7. In combination a tank wherein the level

of liquid may vary, closed to atmosphere except for a vent which is normally open, and having a passage from said vent to a lower part of the tank where the opening of the tank to the vent is, and having a flexible diaphragm in the wall of the tank above said opening, whereby air is sealed in the part containing the diaphragm when liquid rises above said opening; and mechanism associated with the diaphragm exteriorly and adapted to be actuated by movement thereof occasioned by rise and fall of said liquid in the tank.

Signed by me at Boston, Massachusetts, this twenty-eighth day of March, 1916.

WILLIAM J. TURNER.
